H. A. DOUGLAS.
REFLECTING ELECTRIC LAMP.
APPLICATION FILED FEB. 19, 1917.

1,261,785.

Patented Apr. 9, 1918.

UNITED STATES PATENT OFFICE.

HARRY A. DOUGLAS, OF BRONSON, MICHIGAN, ASSIGNOR TO DOUGLAS & RUDD MFG. CO.,
OF BRONSON, MICHIGAN, A CORPORATION OF MICHIGAN.

REFLECTING ELECTRIC LAMP.

1,261,785.

Specification of Letters Patent. Patented Apr. 9, 1918.

Application filed February 19, 1917. Serial No. 149,666.

To all whom it may concern:

Be it known that I, HARRY A. DOUGLAS, citizen of the United States, residing at Bronson, in the county of Branch and State 5 of Michigan, have invented a certain new and useful Improvement in Reflecting Electric Lamps, of which the following is a full, clear, concise, and exact description.

My invention relates to reflecting electric 10 lamps and has for its object the provision of improved means whereby the lamps may be cut in and out of circuit. In my invention there are included a shell constituting a holder and having a lamp bulb at its for- 15 ward end and a switching plug to the rear of the bulb, these parts being located in front of the casing that is a distinct element from the concave reflector, a space intervening between the rear portions of the casing and 20 reflector. A switching rod is preferably coupled with the switching plug and is operable from the exterior of the casing to enable the lamp to be switched in and out of circuit.

25 In the preferred embodiment of the invention the switching is accomplished by turning the switching plug with reference to the shell in which event the switching contacts are eccentric with respect to the shell so that 30 they may be brought into and out of connection according to the movement of the plug. The bulb is desirably adjustable for focusing, etc. The rod may be pushed in and out to secure the focal adjustment, the bulb 35 holding shell having sliding engagement with the holder that is carried by the lamp structure and which shell is held in adjusted positions by means of a spring structure exerting its pressure transversely of the 40 shell.

I will explain my invention more fully by reference to the accompanying drawing showing the preferred embodiment thereof and in which Figure 1 is a side elevation, 45 partially in section, of a reflecting lamp containing features of my invention; Fig. 2 is a longitudinal view, partially in section and partially in elevation, of portions of the structure illustrated in Fig. 1; Fig. 3 is a 50 view on line 3—3 of Fig. 4; and Fig. 4 is a view on line 4—4 of Fig. 3.

Like parts are indicated by similar characters of reference throughout the different figures.

55 The concave reflector 1 is received in the

reflector carrying concave casing 2 which is distinct from the reflector. These elements 1 and 2 are coupled in any suitable way, a space intervening between the rear portions of the reflector and casing 3. The reflector 60 carries a holder or mounting 3 that projects rearwardly from the rear portion of the reflector into the space between the reflector and casing. A spring tongue 4 is integrally formed with a shell 5 that constitutes a 65 holder for contact carriers, this spring tongue having ample clearness at its side margins to permit it freely to function. Some part of the tongue, preferably the rear free end thereof, has a part 6 projecting 70 therefrom which is narrower than the balance of the tongue and is slightly narrower than a slot 7 in the holder 3 whereby this portion may project into the slot to prevent the shell from turning with respect to the 75 slot while at the same time the side margins of the tongue 4 are adapted to press against the side margins of the slot 7. The tongue thus presses upon a surface of the holder 3 and, where there is but one tongue, forces 80 the shell toward the opposite side of the holder whereby the shell is held in engagement with the holder 3. The slot 7 is elongated so that the shell 5 may be moved forwardly and rearwardly in its holder 3 whereby in the structure illustrated the position of the lamp bulb 8 which is carried by the forward end of the shell in front of the reflector may be focally adjusted with respect 85 to the reflector. The base 9 of the lamp bulb 8 constitutes the forward contact carrier and as the arrangement illustrated is a double pole arrangement this contact carrier 9 carries two rear contacts 10 and 11. The lamp base or contact carrier 9 is provided 90 with bayonet pins (of which one 12 is shown) engageable within bayonet seats (of which one 13 is shown) constituting parts of bayonet slots 14. The rear contact carrying plug 15 within the space between the rear 95 portions of the casing and reflector is provided with terminal blocks 16 having binding screws 17 by which circuit wires may be secured to the terminal blocks. These terminal blocks are cylindrical and the forward 100 ends thereof are tubular, springs (of which one 18 is shown) being included in the tubular portions of the terminal blocks and operating to press contacts 19, 20 forwardly into engagement with the contacts 10 and 11, all 105 110

of these contacts being within the back element. The springs 18 and the contacts 19 and 20 thus not only serve to establish circuit for the lamp but also operate to hold the 5 lamp base 9 in bayonet pin and slot connection with the shell 5. The part of the structure thus far described in connection with the accompanying drawing is disclosed and claimed in my co-pending application Serial 10 No. 149,667, filed February 19, 1917.

The plug 15 is preferably rotatable within the rear end of the shell 5 in order that it may perform its switching function and when thus movably mounted it is desirably 15 provided with bayonet pins (of which one 21 is shown) and which are receivable in alternate bayonet seats (of which a pair 22, 23 is shown), the plug being desirably inserted from the front end of the shell with 20 its pins passing along the bayonet slots 14 until they are in the zone that includes the bayonet seats 22, 23 whereafter the base of the lamp bulb is inserted in the shell with its pins 12 placed in the bayonet seats 13. 25 The springs 18 thus not only serve to hold the bayonet pins 12 in the seats but also serve to hold the bayonet pins 21 in the seats to which they are adjusted. The construction of a connector comprising a shell and contact carriers at opposite ends thereof that are passed into the same end of the shell in 30 assembling the parts of the connector is claimed in my co-pending application, Serial No. 149,664, filed February 19, 1917. While 35 I prefer to employ this construction in practising my present invention I do not wish to be limited thereto.

It will be observed that the complementary switching contacts 10 and 19 are eccentric 40 with respect to the shell as are also the complementary switching contacts 11 and 20 so that as the plug is turned these contacts are either brought into engagement or are separated according to the direction of movement 45 of the switching plug 15. When the lamp is in open circuit the contacts 19 and 20 are pressed against the insulating portions of the lamp base that are adjacent the contacts 10 and 11, the springs 18 continuing to press 50 the contacts 19 and 20 forwardly to maintain the bayonet pins upon the switching plug and upon the lamp base in their respective bayonet seats. The shell and the parts within it are in front of the casing 2 and in 55 order that the switching plug 15 may be turned with respect to the lamp base to cut the lamp in and out of circuit I employ a motion transmitting connection, preferably in the form of a forwardly and rearwardly 60 movable and rotatable switching rod or motion transmitting element 24, which is connected at its inner end with the switching

plug (which is movable back and forth) and which rod is extended rearwardly to be operable from the exterior of the casing. The 65 rear or outer end of this switching rod desirably has a gripping head piece 25 fixedly assembled therewith by means of a pin 26 whereby the rod and its head are movable together. This head piece may be gripped 70 in order that the rod 24 may be turned into on or off circuit positions and may be moved forwardly and rearwardly to effect focal adjustment of the bulb. The particular form of lamp illustrated is what is known as a 75 "spot light" but to which form of lamp the invention is not to be limited. When the lamp is in the form of a "spot light" the casing is provided with a handle 21 and this handle I preferably constitute a rearward 80 continuation of the casing, the switching rod 24 passing through the handle to a point where it is operable from the exterior of the casing.

Any suitable means may be employed for 85 establishing circuit relation between the contacts upon the plug 15 and the external source of current, there being illustrated a well known form of connector 15¹ which may be employed for this purpose.

I claim:

In a reflecting electric lamp, the combination with a casing; of a reflector in front of the casing, a space intervening between the rear portions of the casing and reflector; 95 an electric lamp bulb; a shell carrying the lamp bulb at its front and movable forwardly and rearwardly to effect focal adjustment of the bulb; a contact carrying plug within the space between the rear portions of the reflector and the casing and coupled with the shell to be movable forwardly and rearwardly therewith in the focal adjustment of the bulb and serving to supply current to the lamp, the plug also being 100 mounted to turn with respect to the shell to cut the lamp in and out of circuit, there being engageable and separable switching contacts in the lamp circuit, one upon the plug; and a forwardly and rearwardly movable 105 and rotatable motion transmitting element connected with and extending rearwardly from the plug and having a gripping head fixed thereto to be movable therewith and which head is operable from the exterior of 110 the casing to turn said plug to switch the lamp into or out of circuit and to move the plug in or out to move the shell and thereby effect focal adjustment of the bulb.

In witness whereof, I h. subscribe 115 my name this 24th day of January, A. D. 1917.

HARRY A. DOUGLAS.
